Filed Apr. 19, 1965, Ser. No. 84,858

Term of patent 14 years

(Cl. D26—14)

FIG. 1

FIG. 2

FIG. 3

FIGURE 1 is a perspective view of a camera housing for surveillance system showing my new design;

FIGURE 2 is a bottom view of said camera housing; and

FIGURE 3 is a side elevational view of said camera housing.

The side opposite that illustrated in FIGURE 3 has substantially the same appearance as the side shown in FIGURE 3 except that three lenses and three facets are seen.

The top, which is not shown, is characterized by a substantially flat, unornamented surface.

We claim:

The ornamental design for a camera housing for surveillance system, substantially as shown and described.
